UNITED STATES PATENT OFFICE.

EDWARD M. ROSENFELD, OF CLEVELAND, OHIO.

RADIATOR.

Application filed March 25, 1922. Serial No. 546,744.

To all whom it may concern:

Be it known that I, EDWARD M. ROSENFELD, a citizen of the United States residing at Cleveland, in the county of Cuyahoga, and State of Ohio, have invented certain new and useful Improvements in Radiators, of which the following is a specification, reference being had to the accompanying drawings.

This invention relates to improvements 10 in radiators, and more particularly to improvements in automobile radiators.

An important object of the invention is to provide a radiator of this type embodying removable sections so constructed that a single section 15 may be removed for repair, replacement or the like and the radiator employed with the section removed.

A further object of the invention is to provide a construction of this character where- 20 by the removal of the sections is greatly facilitated.

A still further object is to provide in a radiator an improved construction whereby assembly and repair of a radiator is materially 25 facilitated without detracting from the appearance of the radiator.

A still further object of the invention is to provide a device of this character which is simple in its construction, durable in service and a general improvement in the art.

These and other objects I attain by the construction and arrangement shown in the accompanying drawings wherein for the purpose of illustration is shown a preferred embodiment of my invention and wherein like reference characters designate like parts throughout.

In the drawings:

Figure 1 is a perspective view of a radiator 40 constructed in accordance with my invention, parts being broken away;

Figure 2 is a transverse sectional view taken therethrough;

Figure 3 is a section on the line 3—3 of 45 Figure 1;

Figure 4 is a section on the line 4—4 of Figure 1;

Figure 5 is a section on the line 5—5 of Figure 1;

Figure 6 is a perspective of the clamp employed; and

Figure 7 shows one method of sealing the openings when a radiation unit has been removed.

Referring now more particularly to the drawings, the numerals 10 and 11 indicate

upper and lower reservoirs and tanks each provided upon the adjacent faces thereof at the ends of such faces with depending flanges 12 to which are secured side members 13 for 60 maintaining the reservoirs 10 and 11 in proper position. Each reservoir is likewise provided upon the face thereof next adjacent the other reservoir with a flange 14 ex- 65 tends longitudinally of the inner edge thereof. The adjacent walls of the radiator are provided with a series of spaced aligned openings 15, and the flanges 14 thereof are provided in alignment with these openings with pairs of spaced openings 16, the purpose 70 of which will presently appear.

The numeral 17 indicates headers each comprising a shell having an enlarged portion 18 terminating in a restricted neck 19 provided with an outstanding flange 20, the 75 opening of the neck corresponding in size to the openings 15 of the reservoirs 10 and 11 and being adapted for alignment with these openings, the flanges 20 engaging the metal of the reservoirs at the sides of the openings 80 15 with the interposition of a gasket 21 having an opening corresponding in size to the openings of the neck and reservoir. The numeral 22 designates a U-shaped header attaching member, the arms 23 of which are 85 bent at their ends to form the hook portions 24 which are adapted to engage in pairs of openings 16. These arms receive therebetween the neck portions 19 of the headers and bear against the flanges 20 of these neck 90 portions. The bight portions of the header attaching plate are relatively widened and provided with openings 25 through which are directed headed securing elements 26 which engage in threaded openings 27 95 formed in the reservoirs 10 and 11, these openings preferably being formed in a ledge provided by pocketing the reservoirs, as at 27^a, at the corners thereof and continuing the metal of the adjacent faces of the reservoirs in these pockets. A lock washer 28 is 100 preferably disposed between the head of the headed element 26 and the attaching plate 22 to prevent rotation of the securing members.

The numeral 29 indicates tube sections 105 each comprising a plurality of tubes and formed by employing a sheet of corrugated material and bending the same longitudinally and securing the free edges thereof together as by welding, as at 30, the corruga- 110 tions of the plate combining to form alternate tubes 31 and dividing walls 32. The

numeral 33 designates fins, each horizontally disposed and each provided with a plurality of openings 34 and each adapted for the reception of a tube unit 29, the openings being preferably six in number. These tube plates combine the tube units to form a radiation unit U, each fin or plate being secured to the tubes of this unit by soldering or the like. To the upper and lower ends of the tubes of each radiation unit U are secured plates 35 having openings 36 similar to the openings 34 of the plates 33 which receive the ends of the tube units 29 and which are welded thereto to form a tight joint. The plates 35 are of such size that they will fit within the enlarged end 18 of the headers 17 and are welded thereto, as at 37. It will be seen that a plurality of radiation units are thus provided each comprising a pair of headers 17, one arranged at each end of the unit, and a plurality of tube units 29 maintained in spaced relation and subdivided longitudinally to provide cooling passages between the units by the plates 33.

25 When a radiation unit U becomes leaky for any reason, the same may be removed by removing the securing elements 26 of the header attaching members 22 thereof and the tube section removed from the radiator. If 30 it is desired to employ the radiator while the tube section is removed gaskets 38 are applied to the openings 15 and plates 39 employed for covering the gaskets and maintained in position by the U-shaped header 35 attaching members 22 in the same manner in which the headers 17 are maintained in position. These sections being exactly similar, a new section may be inserted in lieu of an old section in but a few moments, it being 40 unnecessary to separate the upper and lower reservoirs to accomplish this object since the units U are free from portions projecting into or interlocking with the reservoirs 10 and 11.

45 In order to maintain the appearance of the radiator I provide cover plates 40 which are attached to the edges of the side members 13 adjacent the adjacent edges of the reservoirs at the front side of the radiator, 50 the attachment being in the form of removable screws or the like so that the plates may be readily removed for access to the header attaching plates 22. These plates are preferably provided with scallops 41 closing the ends of the pockets 27^a and giving the solid portion of the front of the radiator a smooth unbroken appearance.

55 From the foregoing it is believed to be obvious that a radiator constructed in accordance with my invention is particularly well adapted for the use for which it is intended by reason of the fact that a radiation unit may be removed and the radiator employed when so desired, and by reason of 60 the fact that the replacement or removal of

a section may be accomplished with the loss of but a few moments time and without removing the radiator from the car since the units are removable from the front face of the radiator. It will furthermore be obvious that the construction hereinbefore set forth is capable of some change and modification without materially departing from the spirit of my invention and I accordingly do not limit myself to such construction except as hereinafter claimed.

75 I claim:

1. In a radiator, upper and lower reservoirs provided in adjacent faces with aligned opposed openings, removable radiation units provided at the ends thereof with headers having openings in their ends alignable with aligned openings of the reservoirs, and means carried by the reservoirs and movable longitudinally of the headers for 80 clamping the headers in position.

2. In a radiator, upper and lower reservoirs provided in adjacent faces with aligned openings, removable radiation units provided at the ends thereof with headers 90 having openings alignable with aligned openings of the reservoirs, means for clamping the headers in position including flanges formed on the adjacent faces of said reservoirs and provided with pairs of openings 95 aligned with the openings of the faces, U-shaped clamping members having the arms thereof engaged in relatively restricted portions of the headers, the ends of the arms being disposed in the pair of openings 100 of the flange corresponding to the opening with which the header is aligned, and means extending through the bight portion of the U-shaped member for forcing the same toward the adjacent reservoir section.

105 3. In a radiator, upper and lower reservoirs provided in adjacent faces with opposed openings, removable radiation units provided at the ends thereof with headers having openings alignable with aligned 110 openings of the reservoirs, means for clamping the headers in position including flanges formed on the adjacent faces of the reservoirs at corresponding sides of the openings thereof and having openings formed therein, and members embracing the headers and having portions engaged in the flange openings and other portions having a connection with the adjacent reservoir at the opposite side of the openings thereof whereby they 115 may be adjusted toward the reservoir to clamp the header thereagainst.

120 4. In a radiator, upper and lower reservoirs provided in adjacent faces with aligned 125 openings, removable radiation units provided at the ends thereof with headers having openings alignable with aligned openings of the reservoirs, means for clamping the headers in position including restricted neck portions formed on said headers and 130

provided at their upper ends with flanges, substantially U-shaped clamping members receiving the neck portions of the headers and abutting the outer faces of the flanges thereof, flanges formed on said reservoirs and having openings in which the ends of the arms of the U-shaped members are disposed, and means engaging the bight portions of the U-shaped members and the adjacent reservoirs for forcing such bight portions toward the reservoirs whereby to clamp the headers against the reservoirs.

5

5. In a radiator, a reservoir provided in a face thereof with an opening and at the edge of such face with a flange having open-

ings formed therein, a radiation unit embodying a header having an opening adapted to coact with the opening of the reservoir and provided at the sides of the opening with an outstanding flange, a U-shaped 20 clamp engaging beneath the flange of the header and having its ends engaged in the openings of the flange of the reservoir, and means extending through the bight portion of the clamp and engaging the reservoir for 25 forcing such bight portion toward the reservoir.

In testimony whereof I hereunto affix my signature.

EDWARD M. ROSENFELD.
